(57) CLAIM

The ornamental design for a paper golf tee, as shown and described.

DESCRIPTION

FIG. 1 is a perspective view of a paper golf tee;
FIG. 2 is a front elevational view thereof;
FIG. 3 is a rear elevational view thereof;
FIG. 4 is a left-side elevational view thereof;
FIG. 5 is a right-side elevational view thereof;
FIG. 6 is a bottom plan view thereof;
FIG. 7 is a top plan view thereof;
FIG. 8 is a perspective view thereof showing the invention holding a golf ball;
FIG. 9 is a perspective view of the unfolded paper golf tee;
and,
FIG. 10 is a front elevational view of the unfolded paper golf tee.
The broken line showing of the golf ball is for the purpose of illustrating environmental structure and forms no part of the claimed design.
